WELL PUMP

Glenn R. Brown, Bartlesville, Okla., assignor of
one-third to J. E. Crawford and one-third to
H. G. Crawford, Bartlesville, Okla.

Application August 31, 1936, Serial No. 98,812

2 Claims. (Cl. 103—226)

This invention relates to pumps for oil and water wells, and its general object is to provide a device for use with pumping mechanism, that makes it possible to use a working barrel or casing, together with a traveling valve or plunger of a greater diameter than the tubing so as to materially increase production with tubing of the usual size, without necessitating the impractical method of removing or pulling the tubing, barrel, 10 plunger and rods at the same time, in the event the plunger or other parts need to be raised for inspection or repairs, as with the use of my device the rod can be readily disconnected and connected with respect to the plunger parts from 15 the surface of the well, regardless of the depth of the latter which of course will allow the rods and casing to be pulled or removed from the well separately.

A further object of the invention is to provide 20 a device of the character set forth, that allows for the free passage of fluid from the plunger and barrel yet prevents foreign matter such as scale, rust and particles of stuffing box packing or the like from getting into the barrel and interfering 25 with the proper function of the traveling valve or plunger.

Another object of the invention is to provide 30 a device that will allow for both attaching and detaching the rods with respect to the plunger parts, from the surface of the well, for the purpose set forth, and the device is simple in construction, inexpensive to manufacture, easy to install and extremely efficient in use, operation 35 and service.

This invention also consists in certain other 40 features of construction and in the combination and arrangement of the several parts, to be hereinafter fully described, illustrated in the accompanying drawing and specifically pointed out in the appended claims.

In describing my invention in detail, reference 45 will be had to the accompanying drawing wherein like characters denote like or corresponding parts throughout the several views, and in which: Figure 1 is a longitudinal sectional view taken through the device which forms the subject matter of the present invention and illustrating the same applied within the barrel and tubing.

Figure 2 is a sectional view taken on approxi- 50 mately line 2—2 of Figure 1 looking in the direction of the arrows.

Figure 3 is a fragmentary side elevation of the major portion of the device.

Referring to the drawing in detail, the reference numeral 1 indicates the barrel, 2 a reducing

collar or nipple and 3 the lower section of the tubing.

Mounted in the barrel is the body 4 of my device which as shown is solid and substantially of cylindrical formation, and has a beveled lower end, with the beveled portion extending into the flat bottom thereof, the latter being provided with a threaded bore, centrally arranged therein to threadedly receive the head 5 of a traveling valve rod 6, as will be apparent.

The body 4 is provided with longitudinally arranged diametrically opposed grooves 7, opening into the sides thereof and through the upper end, as clearly shown in Figure 1, and pivotally mounted in the lower ends of the grooves 7, to 15 extend above the upper end of the body 4, are dogs 8 which are provided with heads 9 on the upper ends thereof, and the heads include inclined or cammed inner surfaces 10 and shoulders 11, at the juncture of the heads with the shanks of the dogs, as clearly shown in Figure 1.

The dogs are spring pressed and are normally held within the grooves by leaf springs 12 that are secured to the body 4 and contact the outer face of the dogs for the major portion of the 25 length thereof.

The upper end of the body is likewise flat and has arranged centrally therein what I term a centering depression or opening 13, for the purpose of guiding and receiving the apex or pointed 30 lower end of the conical head portion 14 of the locking member of my device which cooperates with the dogs 8, the locking member being provided with a shank 15 of smaller diameter than the head, to provide a shoulder 16 to receive the 35 hooked portions or shoulders of the heads of the dogs, and the shoulders 16 are shown as being slightly depressed or downwardly inclined toward the shank to assure positive connection between the heads of the dogs and the locking member which is likewise provided with a threaded 40 upper end 17, to be threadedly mounted in the lower end of what I term a guide tube 18 which extends through the collar, for disposal within the tubing, as shown. The upper end of the guide 45 tube is likewise threaded to receive the threaded head of the lower section 19 of the rod.

Threadedly secured to the collar 2, and having a bore therethrough to slidably receive the guide tube 18, for passage therethrough, is a plug member 50 20 that is provided with a flat upper end and a beveled lower end 21, the bevel of which follows the inclination of the cammed surface 10 of the heads of the dogs 8 for cooperation therewith for a purpose which will be presently de- 55

scribed. The plug member 20 is provided with a plurality of passages or bores 22, for the passage of fluid from the barrel into the tubing, as will be apparent, and the passages 22 are relatively small in diameter, so as to prevent the downward passage of foreign matter, such as scale, rust and particles of stuffing box packing or the like into the barrel thereby preventing the same from interfering with the proper function of the traveling valve or plunger.

It is believed that it will be obvious from the above description and disclosure of the drawing, that the operation of my device will be apparent, but it might be mentioned that the body 4 is disposed within the barrel 1, in assembling the device, after rod 6 is threaded in the lower end of the body. The plug member 20 is threaded on the collar and the collar is then threaded on the lower barrel, the collar being threaded on the lower section of the tubing, which together with the collar, barrel and the parts within the latter are let into the wall. The locking member is threaded on the lower end of the guide tube which in turn is threaded on the lower section of the rods, and these parts are run in the usual way. When the locking member contacts the cammed inner surface 10 of the dogs 8, it will be obvious that the head portions of the locking member will spread the dogs, to cause the hooked portions thereof to contact the depressed shoulder 16, thereby locking the rods to the body. The well is then ready to operate in the usual way. When the rods are to be pulled from the well, upward movement thereof will cause the cammed inner surface 10 to contact the beveled lower end 21 of the plug member, thereby separating the dogs and moving the hooked upper ends from the locking member, as will be apparent, consequently it will be seen that the rods can be readily connected and disconnected with respect to the plunger parts, from the surface of the well, in an easy and expeditious manner and with minimum effort.

It is thought from the foregoing description that the advantages and novel features of my invention will be readily apparent.

I desire it to be understood that I may make changes in the construction and in the combination and arrangement of the several parts, pro-

vided that such changes fall within the scope of the appended claims.

What I claim is:

1. In combination a plunger barrel, a body disposed in the plunger and having diametrically opposed grooves arranged longitudinally therein, dogs pivotally secured to the body and normally disposed in the grooves, the pivots for the dogs being disposed within the confines of said body, leaf springs secured to said body at points below the pivots for the dog and contacting the dogs throughout the major portion of the length of the dogs, a guide tube for connection with the pump rods and having its lower end portion inferiorly screw threaded, a locking member having an enlarged upper end exteriorly screw threaded for detachable connection with the interior threaded portion of said guide tube, said member having a conical head and constricted intermediate portion, whereby an annular shoulder is provided at the upper end of the head, said shoulder being downwardly inclined towards the center thereof, said head being engageable with the dogs for separating the dogs for engagement with the shoulder, and a plug for the pump barrel having a beveled lower surface arranged in the path of the dogs to remove the dogs from the shoulder.

2. In combination a string of tubing, a plunger barrel having a greater diameter than that of the tubing, spring pressed dogs pivotally mounted within said plunger barrel and having cammed upper ends, a guide tube for connection with the pump rods and to extend within the barrel, a locking member secured to the guide tube and including an annular shoulder and a conical shaped head at its lower end adapted to spread said spring pressed dogs to enable the dogs to engage said shoulder, a reducing collar having its larger end attached to the upper end of the plunger barrel and its smaller end attached to the lower section of tubing, and a plug having through passages therein attached to the reducing collar and having its lower end beveled and adapted upon upward pull of the rods to engage the cammed surfaces of the dogs to disengage the dogs from said shoulder.

GLINN R. BROWN.
